ALVIN WELLING, OF COVINGTON, KENTUCKY.

BOTTLING-MACHINE.

1,232,137.

Specification of Letters Patent.

Patented July 3, 1917.

Application filed November 3, 1914. Serial No. 870,145.

To all whom it may concern:

Be it known that I, ALVIN WELLING, a citizen of the United States, and a resident of Covington, in the county of Kenton and State of Kentucky, have invented a certain new and useful Improvement in Bottling-Machines, of which the following is a specification.

This invention has relation to bottling-machines or, more particularly speaking, to that part of a bottling-machine used in successively or intermittently feeding the respective bottles up to the filling and capping devices in an upper cross-head of the machine. The object of the invention is to provide means to compensate for the loss in wear and tear of the bottle-dial operating parts that include the usual ratchet-wheel, pawl, lever and cam devices ordinarily inclosed in the lower or supporting part of the frame beneath the working platform or table (on which the bottles are set or placed in upright position) so that they can not be readily or conveniently reached for inspection or repairs without dismantling the said lower part of the machine that deprives the use of the machine for considerable time. Heretofore, the wear and tear in the said lower working parts and in the bottle-dial itself have caused lack of control in accurately locating and timing the said bottle-dial, it being the purpose of the said ratchet and pawl mechanism, and especially of each stroke thereof, to positively locate and set in true vertical alinement each rim-opening or bottle holder-cup of the dial under the center of the filling-head as it advances in the intermittent rotary movement of said dial. If said bottle holder-cup is not in true alinement or center it will cause strain on the adjacent parts of said filling-head and material loss in effecting air-tight joints when filling the bottles, and in the waste of the liquids to be placed in the bottles. The use of the machine and the saving of valuable time taken in overlooking and repairing it are material points accomplished by me in the application of my extremely simple and economical invention herein, the same being hereinafter fully described and then particularly pointed out in the claim.

In the accompanying sheet of drawings, Figure 1 is a front elevation of a bottling-machine in connection with which my invention is particularly adapted and shown, the

central part of the upper filler-head being shown in section, a part of the bottle-dial shown in section, and the inner or hidden lower ratchet-wheel shown in section, with parts of the lower supporting-frame broken away; Fig. 2, a plan showing the usual ratchet-and-pawl mechanism adapted to the intermittent rotation of the bottle-dial and its vertical shaft, the latter being shown in section; Fig. 3, a side elevation of my improved special form of coupling or clamping ring used in securing the bottle-dial on the upper end of said shaft; Fig. 4, a plan view of the said coupling-ring seen in Fig. 3 but with the gripping-screw in place and showing the vertical shaft in section; Fig. 5, a central section of the said coupling-ring seen in Fig. 4, taken along the open or split portion thereof and showing the gripping-screw in section; Fig. 6, a group elevation of the gripping-screw, that includes an end view of the shank and peculiar form of head with one flat side to prevent turning; Fig. 7, a group elevation showing a side and front view of the nut used on said gripping-screw; Fig. 8, a side elevation of a convenient key used in operating the nut seen in Fig. 7; Fig. 9, a fore-end view of the key seen in Fig. 8; and Fig. 10, a detached elevation showing my improved clamping-ring in position on the vertical dial-shaft (but at right-angles to the position seen in Fig. 1) and a side view of the table (broken off at its fore end), together with a section of the web of the dial, an elevation of the dial-hub, an elevation of the plunger-shaft that engages the hub-support of the said table, and an elevation of the lower lugged cap-plate and a screw used on the top of the vertical shaft to secure the dial in removably-attached place for turning with said shaft.

1 indicates the lower supporting-leg or base portion of the machine in which is located the vertical shaft 2, the horizontal ratchet-wheel 3 keyed on said shaft, the spring-controlled pawl 4, the pivoted lever 5 carried by the arm 6 and carrying at its outer end the cam-engaging roller 7, all as in general use in this class of machines. These parts are hidden within the supporting-leg portion of the machine and very difficult to reach for inspection and repairs, when worn or loose, or accidentally out of place, and it is necessary to dismantle the machine to make such repairs and take up

wear and looseness that otherwise cause the dial to rotate in a loose and defective manner and lessen the control of the operator in accurately timing or locating it so that the 5 successive empty bottles carried thereby shall approach the central opening in the filling and capping head of the machine.

The vertical shaft 2 extends upwardly from the base 1 through the immovable plat- 10 form or table 8 that is carried by a hub 9 properly connected with the base of the ma- chine. The bottom of the table has a central hollow boss 9, and a duly fastened sleeve 10 is used on the shaft 2, contacting with the 15 said boss 9, to prevent upward play or thrust of the shaft.

The bottle-dial 11 has a circular series of 20 openings or bottomless cups 12 in its rim for the empty bottles and is provided with a central hub 13 having a web 14 that carries the said cupped rim as customary. The lower portion of the hub 13, however, is provided with a pair of radial notches or 25 grooves 15 and the upper portion thereof with similar notches or grooves 16.

17 indicates a cap-plate having radial ribs or tongues 18 that engage the said notches or grooves 16 in the upper face of the dial-hub 13, and the center of the cap-plate is pierced 30 to receive the shank of a vertical screw 19 that enters a threaded socket in the top of the shaft 2 for securing the cap-plate in place, and the interlocking of the tongues 18 with the notches 16 duly couples the dial 35 with the shaft at the top of the latter so as to be rotated by the latter in intermittently advancing the empty bottles up to filling and capping position.

An auxiliary coupling-member or clamp- 40 ing-ring 20, however, is used by me in positively securing the dial on the shaft so that it maintains a constant place thereon for the accurate delivery of the successive empty bottles to the plunger 21 for the raising of 45 said bottles to the filling and capping point 22 in the center of the upper cross-head 23 that is supported by means of the pillars 24, 24 at the rear part of the machine.

The coupling-member 20 forms the essen- 50 tial feature of the invention herein and is composed of a ring that is split at 25 and has laterally projecting lugs 26, 26 that are pierced to accommodate the bolt 27, the lat- 55 ter having an outer head 28 and a nut 29, and a lock-spring washer 30 being used be-

tween the nut 29 and the adjacent lug 26 to prevent the nut becoming accidentally disengaged or loosened. The head 28 of the bolt is preferably a round one with one flat side 28^a that engages the side of the clamp- 60 ing-ring 20 and prevents its rotating in the turning up or the turning off of the nut 29. The nut 29 is preferably a circular one with a pair of radial grooves 29^a, and a key 31 is used to operate it, such key having lugs 65 32 that engage the grooves 29^a in the convenient manner adapted thereby in handling the clamping-ring on the shaft 2. The clamping-ring has a pair of radial tongues or ribs 33, 33 on its upper face and they are 70 suitably beveled so as to readily engage the grooves 15 in the bottom of the dial-hub 13 for the interlocking of the clamping-ring with the dial.

The turning of the nut on the bolt 27 75 home with the key 31 draws the two lugs 26, 26 together so as to cause the ring 20 to firmly and tightly clamp or grip the shaft 2 when once the said dial is properly arranged on the said shaft to timely locate the suc- 80 cessive bottles under the filling and capping devices of the machine, and to positively maintain such relation at all times, especially when there is any of the wear and looseness in the parts hereinbefore amply 85 referred to, at which time a quick and easy adjustment can be made by loosening the clamping-ring on the shaft and then tightening it as soon as the dial has been duly 90 located and timed.

I claim:—

In a bottling-machine, a vertical shaft, a horizontal, clamp-coupling split ring adapted to be loosely as well as firmly mounted on the shaft and having laterally-projecting 95 pierced lugs at its split portion, a horizontal bolt having a nut and engaging said pierced lugs, a resilient washer on said bolt between the nut and one of said lugs, vertically-extending means on the upper face of the split 100 ring, and a horizontal bottle-dial on said shaft and having a grooved hub that is adapted to coöperate with said extending means on the split ring for interlocking the latter and said dial on said shaft.

ALVIN WELLING.
